GAS BURNER

John E. Cunningham, El Paso, Tex., assignor to
Peeler-Hansen Stove and Foundry Company,
El Paso, Tex.

Application June 6, 1933, Serial No. 674,594

6 Claims. (Cl. 158—108)

This invention relates in general to a gas burner and more particularly to a burner designed to promote complete combustion of all combustible materials contained in or making up any gaseous fuels.

In the past, it has been customary in burners for gaseous fuels to either supply the air by force at a point immediately adjacent the gas outlet, or to admix the gas with air prior to combustion. Both of these methods have been found to be unsatisfactory in that first of all they are inefficient since they do not cause a complete combustion of all the combustible materials contained in the gas. Secondly, there is no way of controlling the exact amount of air to be used in the combustion because of the fact that combustion as a rule takes place in the open air and thus makes use partly of cold air from the atmosphere and partly of the air supplied to it as just set forth.

It is an object of this invention to provide a gas burner in which the air supplied for the purpose of combustion may be positively controlled according to the requirements of the particular gaseous fuel being used. Also, it is an object that this air shall be supplied to the burner in heated form, a part of the air being first supplied as a primary air supply to cause combustion and expansion of the carbon or like content of the gases while at the same time furnishing heat for heating the secondary air and for raising the hydrogen content of the gases to the ignition point of hydrogen.

It is an object of this invention that the gas and both the primary and the secondary air shall be released in a primary expansion chamber where primary expansion of the gas takes place. It is an object that part of the gas outlet orifices shall be arranged to direct the expanding gas against a refractory wall provided for the purpose and that the secondary air shall be injected into the primary expansion chamber in such a direction as to cut down the velocity of the primary expansion or combustion of gas and prevent a too rapid primary expansion.

Other objects and advantages of this invention will become apparent from the following description taken in connection with the accompanying drawing, it being distinctly understood that the same are by way of illustration and example only and are not to be taken as in any way limiting the spirit or scope of this invention. The spirit and scope of this invention is to be limited only by the accompanying claims taken in connection with the prior art.

55 Referring now more particularly to the draw-

ing in which like numerals indicate corresponding parts throughout:

Figure 1 is a vertical cross section of a burner constructed in accordance with this invention.

Figure 2 is a bottom plan view of the device illustrated in Figure 1.

Figure 3 is a rear view of the same construction.

Figure 4 is a section taken along the line 4—4 of Figure 2.

Figure 5 is a view partly broken away illustrating a portion of the primary air heater.

In accordance with this invention, the same consists in general of a gas distributor 1, a primary air heater 5, a secondary air heater 2, an air control valve 3, and a primary expansion chamber 21.

The gas distributor 1 consists of a hollow block resting on a support 13 which in turn is supported by the bottom support plate or base plate 10. Gas is supplied to the distributor 1 by means of the gas manifold 4 which is secured to the bottom of the distributor by means of screws 14 extending through holes 25. The end 39 of the manifold 4 is positioned to register with the opening 40 provided in the gas distributor, whereby gas may pass from the end to the gas distributor block 1. As illustrated, the gas manifold 4 is supplied by means of a gas supply pipe 11 having its end 31 connected to the manifold inlet 38. The gas distributor is provided on its upper surface with a pair of orifice bosses 23a and 23b respectively through which are formed orifices 24a and 24b at various intervals, these forming the outlet orifices for the gas. It is to be noted at this point that while the orifices 24b are open in a substantially vertical direction, the orifices 24a are disposed at an inclination so as to be directed away from the secondary air heater 2.

The primary heater 5 consists of a bottom plate 19 forming an integral part of the distributor block 1 and extending laterally and at a slight inclination upwardly therefrom to a point adjacent the rear wall 9 of the burner. This rear wall 9 is held in place by means of bolts 15 passing through flanges on the base plate 10 and the end plates 7a and 7b respectively and through holes 37 in the plate 9. At a point adjacent the outer extremity of the bottom plate 19 of the primary air heater, the rear wall 9 is provided with an integral lug 26 adapted to support the outer edge of the top plate of the primary air heater. This primary air heater top plate is provided with downwardly extending air heater fingers 27, these fingers being of such shape that

their lower surfaces will contact with the upper surface of the bottom plate 19, and at the same time being gradually decreased in width from their outer extremities to their inner extremities 5 as indicated in Figure 5. The top plate is anchored to the bottom plate 19 by means of screws 25a engaging the threaded holes 36 in the bottom plate. The inner edge of the top plate is spaced from the upper edge of the distributor block 1 so as to form an opening or exhaust port 20 for the primary air heater, through which exhaust port the heated primary air passes into the primary expansion chamber 21.

The secondary air heater 2 consists of a grill 15 resting on the burner base plate 10 and positioned by lugs 28 which are integral with the base plate 10. This grill is further positioned by the refractory walls 8 on the burner end plates 7a and 7b, and contacts at its upper edge with 20 the burner front plate or air deflector 6 at its upper edge 35. The secondary air heater 2 as illustrated is provided with openings or louvres 22 therein for the purpose of admitting the secondary air through the primary expansion chamber 21 and directing it upwardly away from the distributor block 1 and at the same time across the primary expansion chamber 21, toward the refractory wall 8 which forms a lining at the ends and back of the primary expansion chamber 21.

30 The burner front plate or air deflector 6 is secured in place by bolts 15 identical with those previously described, these bolts securing this deflector plate to the bottom or base plate 10 and to the end plates 7a and 7b respectively.

35 The base plate 10 is provided with openings 33 for the purpose of admitting the branches of the gas manifold 4, and is provided with an elongated opening forming the two air inlets 18a and 18b for the primary and secondary air supplies respectively.

40 At the opposite ends of this elongated opening, the base plate 10 is provided with upstanding lugs 29 having drilled holes therethrough for a purpose to be described. Of substantially the same size as this opening and having corresponding lugs 30 adapted to register with the lugs 29 45 is the air inlet control valve 3 which has been previously mentioned. Pins 12 are passed through the openings in the lugs 29 and 30 respectively thus hinging the controller valve 3 to swing within the opening to open and close the same.

45 Extending outwardly toward the controller valve 3 and integral with the distributor block 1 there is provided an air dividing plate 17. This plate projects downwardly and forwardly from the front lower edge of the gas distributor 1 and has for its purpose to maintain the division 50 of the primary and secondary air as made by the valve 3 passing through the air inlet openings 18a and 18b. As will be noted, this dividing plate extends to such a position that when the valve 3 is opened it will contact along one edge with the dividing plate, thereby forming a continuous wall from the opening through the base plate to the primary heater 5 and the secondary heater 2.

70 It will be seen from the above that when this burner is in operation gas will be passed through the supply pipe 11 and the manifold 4 into the distributor block 1 and out through the orifices 24a and 24b respectively. At the same time, air will be drawn in through the ports 18a and 18b, the primary air being separated by the divider plate 17 and conveyed past the manifold 4 into

the openings 16 between the primary air heater fingers 27. As it passes through these openings it is heated by heat from the primary expansion chamber. It then passes outwardly through the primary air heater exhaust port 20 and is then mingled with the gas being emitted from the orifices 24a and 24b at a point immediately adjacent these orifices. At this point, there occurs the chemical combination of the carbon content of the gaseous fuel. This not only heats the hydrogen content of the gaseous fuel to its ignition point, but at the same time furnishes heat to the secondary air heater 2 so that the secondary air is injected into the primary expansion chamber 21 at a very high temperature. This secondary air being directed upwardly toward the opening 41 in the primary expansion chamber and at the same time transversely of the expansion chamber toward the refractory lining plate, serves to slow up the movement of the gases during the primary expansion stage and to prevent a too rapid expansion which would cause vibration within the burner. As the gaseous fuel reaches the outlet 41 of the primary chamber it combines with the secondary heated air and the combustion of the gas is thereupon completed as it leaves the primary expansion chamber.

90 It will be seen from the above that a very efficient and valuable burner has been provided which carries out all of the objects set forth in connection with this invention. It is apparent, however, that the illustration is by way of example only and that various changes and modifications may be made in the details and arrangement of parts without departing from the spirit 100 or scope of this invention as defined by the appended claims.

105 What I claim is:—

110 1. In a gas burner, a primary expansion chamber open at its top, a gas distributor disposed at the bottom of said chamber and having upwardly directed orifices therein, a primary air heater adjacent one side of said distributor and having its outlet opening into said primary expansion chamber adjacent said orifices, a secondary air heater disposed to the other side of and above said orifices, said secondary air heater having outlets formed to direct the heated secondary air upwardly away from the distributor and toward the open end of the primary expansion chamber, a common controlling valve for supplying both the primary and the secondary air, the orifices in said distributor nearest the outlet for the primary air heater being directed substantially straight upwardly, the orifices in 120 said distributor nearest the secondary air heater being directed upwardly at an inclination away from said secondary air heater, and a refractory wall for the side of the primary expansion chamber toward which said last mentioned orifices 125 are directed.

130 2. In a gas burner, a primary expansion chamber open at its top, a gas distributor disposed at the bottom of said chamber and having upwardly directed outlet orifices therein, a primary air heater adjacent one side of said distributor and having its outlet opening into said primary expansion chamber adjacent said orifices, a secondary air heater disposed to the other side of and above said orifices, said secondary air heater having outlets formed to direct the heated secondary air upwardly away from the distributor and toward the open end of the primary expansion chamber, a common controlling valve for supplying both the primary and the secondary air, the 140

- orifices in said distributor nearest the outlet for the primary air heater being directed substantially straight upwardly, and the orifices in said distributor nearest the secondary air heater being directed upwardly at an inclination away from said secondary air heater.
3. In a gas burner, a gas distributor having outlet orifices therein, a primary air heater adjacent one side of said distributor and having its outlet adjacent to said orifices, a secondary air heater disposed to the other side of and above said orifices, said secondary air heater having outlets formed to direct the heated secondary air upwardly and away from the distributor, a common controlling valve for supplying both the primary and the secondary air, the orifices in said distributor nearest the outlet for the primary air heater being directed substantially straight upwardly, and the orifices in said distributor nearest the secondary air heater being directed upwardly at an inclination away from said secondary air heater.
4. In a gas burner, a primary expansion chamber, a gas distributor therein having gas outlet orifices, means for injecting heated primary air into said primary expansion chamber adjacent said orifices to cause primary partial combustion of the fuel within the chamber, means for injecting heated secondary air into said chamber above said distributor, whereby the rapidity of primary combustion within the chamber will be checked and complete combustion will be promoted as the fuel leaves the chamber, and common volume control means for controlling and separately admitting said primary and secondary air and main-
- taining a substantially constant proportion therebetween regardless of the volume of air admitted.
5. In a gas burner, a gas distributor having outlet openings therein, a primary air heater adjacent one side of said distributor and having its outlet adjacent to said openings, a secondary air heater disposed to the other side of and above said openings, the openings in said distributor nearest the outlet for the primary air heater being directed substantially straight upwardly, and the orifices in said distributor nearest the secondary air heater being directed upwardly at an inclination away from said secondary air heater.
6. In a gas burner, a primary expansion chamber, a gas distributor therein having gas outlet orifices, means for injecting heated primary air into said primary expansion chamber adjacent said orifices to cause primary partial combustion of the fuel within the chamber, means for injecting heated secondary air into said chamber above said distributor, whereby the rapidity of primary combustion within the chamber will be checked and complete combustion will be promoted as the fuel leaves the chamber, a butterfly valve for controlling the admission of said primary and secondary air and for receiving the primary air on one side thereof and the secondary air on the other side thereof to maintain a substantially constant proportion therebetween, and means inwardly of and adjacent said butterfly valve for cooperating with the butterfly valve in maintaining the division between the primary and secondary air.
